3 Claims. (Cl. 315—39)

The invention relates to a device for concentrating the electron beam of a high-power klystron having more than two cavity resonators, in with the magnetic fields, alternating their directions, are produced by means of permanent magnets with pole shoes contacting the drift tube parts of the klystron.

Devices of the kind set forth are known and shown diagrammatically in FIG. 1. The alternating magnetic fields 3 travel between pole shoes 5 and the permanent magnets are designated by 7. The direction of movement of the electron beam is denoted by 1. With high-power klystrons having more than two cavity resonators, which usually operate on comparatively low frequencies, such a structure brings about, however, inconvenient dimensions and weights, not only of the assembly as a whole but also of the component parts, since in this case the large resonators must be bridged by the soft-iron yokes between the pole shoes 5 and the magnets 7.

With low-power two-cavity klystrons it is known to arrange, between the two cavities, a short, single lens, which is excited by an electro-magnet; this may, however, also be a permanent magnet. With a klystron having more than two cavity resonators the arrangement shown diagrammatically in FIG. 2 would be obtained, in which, like in FIG. 1, 1 designates the direction of travel of the electron beam and 5 the pole shoes. The walls of the drift tube are designated by 11 and the magnetic rings by 13, which produce magnet fields indicated by arrows between the pole shoes 5. However, this arrangement cannot be used in those cases in which the walls of the drift tube must be cooled by air, since this requires cooling vanes of a fairly large diameter with the associated cold-air pipes. A further great disadvantage of such a concentration by means of magnetic single lenses would be that just in the region of the inductance gaps and modulation gaps 15 of the cavity resonators 17 the diameter of the electron beam has a minimum, which will be seen from the drawing by the cross-hatched section of the electron beam. Because of the small beam diameter a heavy coupling between the electron beam and the cavity resonators would not be possible. This is, however, possible, if the diameter of the electron beam approaches more closely that of the interaction gap.

In a device for concentrating the electron beam in a high-power klystron having more than two cavity resonators, in which the magnetic fields of alternating directions are produced by means of permanent magnets, having pole shoes contacting the parts of the drift tube of the klystron, the permanent magnets are arranged, in accordance with the invention, at a given distance from the walls of the drift tube outside the cooling members and are connected by magnetic yokes with the pole shoes, which extend on either side of the yokes in an axial direction over a distance such that axial magnetic fields are produced also in the spaces inside the cavity resonators, which fields have the opposite direction as compared with those of the drift tube parts and have approximately the same intensity. With the structure according to the in-

2

vention a periodic, axial magnetic field is obtained throughout the length of the klystron without the need for bridging the cavity resonators by magnetic yokes. With this arrangement the electron beam may, moreover, have a maximum diameter in the interaction space inside the cavity resonators, so that a heavy coupling between the beam and the cavity resonators is possible.

A simple control of the magnetic field intensity may be obtained when the magnets consist of magnetic columns composed of parts, which are relatively slidable, so that a more or less strong leakage field can be adjusted.

If sintered, oxidic permanent magnets are employed, the two pole shoes may be at different potentials, which is advantageous with certain tubes.

In accordance with the invention the magnetic columns may be connected with the yokes, which are fastened by means of bolts or the like to the pole shoes.

The arrangement according to the invention, when sintered, oxidic magnets are employed, consists in that the influence of temperature of the air-cooled parts on the magnets is only slight, so that from this side the magnetic field is little affected by temperature.

The invention will now be described more fully with reference to FIGS. 3 to 5, of which

FIG. 3 shows diagrammatically a longitudinal sectional view of a device according to the invention.

FIG. 4 is a plan view and

FIG. 5 is a cross sectional view.

As is shown in FIG. 3 resonators 17 are arranged between the parts 11 of the drift tube. The parts 11 of the drift tube are provided with cooling vanes 19. In FIG. 5 the direction of travel of the cooling air is indicated by arrows 20. Between the outer vane 21 and the walls 23 of the resonators there are arranged pole shoes 25, which are connected via soft-iron yokes 27, with the magnetic columns 29, shown diagrammatically. These columns 29 are disposed towards the outer side to an extent such that they do not hinder the cooling operation. The columns 29 consist of stacked, oxidic magnets.

Inside the drift tube parts 11, in the regions 31, magnetic fields B_a are produced in the direction of travel of the electron beam 1, if the magnetic columns 29 are all oriented in the same direction. However, magnetic fields B_b in opposite direction are produced at the same time in the high-frequency interaction spaces 34 away from the pole shoes 25. Because of the periodic magnetic field along the electron beam 1 the variations in diameter of the beam are considerably smaller than in the arrangement of FIG. 2; in the regions 34 the electron beam has approximately its maximum diameter, so that a fixed coupling with the cavity resonators is possible. The same intensity of the magnetic fields B_a and B_b is obtained by the choice of the pole shoe parts c and d on either side of the yokes 27, so that the lengths a and b of the magnetic field portions in the drift tube and in the cavity resonator respectively can be adjusted.

From FIGS. 4 and 5 it will be seen that the magnetic yokes comprise parts 37, which are connected with the pole shoes 25, and parts 43, between which parts the magnetic columns are arranged, which are provided with flanges 39 and 41 respectively of non-magnetic material. The magnetic columns consist of two discs 45, glued to the yoke parts 43 and having arranged between them a disc 47, which is slidable along guide rods 49. To this end connecting rods 50, provided with screw threads, are coupled with screw-threaded bars 51, which can be turned by means of a hand-wheel 53. The two halves of the screw-threaded bar 51 are intercoupled at 55. By displacing the discs 47 by turning the screw-threaded bar 51, the intensity of the magnetic field can be adjusted.

The device according to the invention may be employed

with klystrons having a resonator diameter of 100 cms.; in the case of four resonators the *overall length is 180 cms.*

What is claimed is:

1. A device for concentrating an electron beam in a drift tube of a klystron having at least three cavity resonators comprising means to cool the drift tube, means for producing magnetic fields in the drift tube alternating in direction between the cavity resonators, said magnetic field producing means including permanent magnets positioned beyond the cooling means and spaced from the drift tube, pole-pieces adjacent to portions of the drift tube between successive cavity resonators, and a yoke of magnetic material connecting each magnet with a pole-piece, each of said pole-pieces extending in the direction of the drift tube on either side of the yoke a distance at which an axial magnetic field is produced in the adjacent cavity

10

5

resonator having approximately a direction opposite to and having the same intensity as that produced in the adjacent section of the drift tube.

2. A device as claimed in claim 1 in which the magnets are constituted of columns having parts displaceable relative to one another.

3. A device as claimed in claim 2 in which the columns are connected with the yokes and the yokes are secured by bolts to the pole shoes.
